UNITED STATES PATENT OFFICE.

JOSEPH WYBORSKI, OF PHILADELPHIA, PENNSYLVANIA.

STREET-CLEANING MACHINE.

1,177,561.

Specification of Letters Patent. Patented Mar. 28, 1916.

Application filed April 16, 1915. Serial No. 21,673.

To all whom it may concern:

Be it known that I, JOSEPH WYBORSKI, a citizen of the United States, residing at Philadelphia, in the county of Philadelphia and State of Pennsylvania, have invented new and useful Improvements in Street-Cleaning Machines, of which the following is a specification.

This invention is an improved street cleaning machine embodying a revoluble brush for sweeping a street surface and also embodying a receptacle for the sweepings and means for loading the sweepings of the brush into the receptacle, the object of the invention being to provide an improved machine of this character which sweeps and gathers the dirt automatically, is simple in construction, is strong and durable, and which can be readily controlled.

The invention consists in the construction, combination and arrangement of devices hereinafter described and claimed.

In the accompanying drawings;—Figure 1 is a side elevation of a street cleaning machine constructed in accordance with my invention with the near wheel removed and the axle spindle of said wheel shown in cross section. Fig. 2 is a plan of my improved street cleaning machine. Fig. 3 is a longitudinal sectional view of the same on the plane indicated by the line *a—a* of Fig. 2. Fig. 4 is a detail rear elevation of the same. Fig. 5 is a detail elevation, partly in section, of the frame. Fig. 6 is a detail sectional view of the box which receives the sweepings. Fig. 7 is a detail perspective view of the arch cross bar.

In the embodiment of my invention I provide an arched rear axle 1 which is connected by reaches 2 to the fifth wheel 3 of a front truck 4 which embodies a front axle 5, front wheel 6, and a draft tongue 7. Rear wheels 8, 9 are mounted on the spindles 10 of the arched axle 1. The wheel 8 is here shown as on the left hand side of the machine. On the inner side of said wheel 8 is a master gear 11 which revolves with said wheel.

A frame 12 trails in rear of the axle 1 and is here shown as comprising a pair of side wires 13 13^a connected together at their rear ends by an arched cross bar 14. The side bars are here shown as tubular and the ends of the arched cross bar are shown as arranged in the rear ends of the tubular side bars and secured thereto by screws 15. At

the front ends of the bars 13 13^a are eyes 16 which are engaged by bolts 17 whereby pivot connections are effected between the frame 12 and the arched axle 1 so that the rear end of the frame may be raised and lowered. A pair of bearings 17 are secured to the bars 13 13^a near the rear ends of said bars and a cylindrical revoluble brush 18 has its shaft 19 mounted in said bearings. This brush is arranged to bear on and sweep the street surface and is revolved in the direction indicated by the arrow in Fig. 1. The shaft 19 is provided at opposite ends with sprocket wheels 20, 21.

A stub shaft 22 has one end mounted in a bearing 23 on the left hand bar 13 and has the other end mounted in a bearing in an angle bracket 24 which is secured to said bar and is arranged, together with said stub shaft projecting from the left hand side of the frame 12. A stub gear 25 is mounted for rotation on said shaft 22, engages the master gear 11, for rotation thereby, and on the inner side of said gear 25 is a clutch member 26. A sprocket wheel 27 is revolvably mounted, is also shiftable on the stub shaft and has a clutch member 28 on one side for engagement with the clutch member 26 and is provided on the opposite side with an annularly grooved hub 29 which is engaged by a shipper lever 29^a. Then the endless sprocket chain 31 connects the sprocket wheels 27 and 20, so that the revoluble brush is driven when the machine is in motion and the wheel 27 is clutched to the gear 25. To operate the shipper lever a hand lever 32 is provided which is pivotally mounted on the arched axle as at 33, is connected to the shipper lever by a link 34 and may be locked in the desired position by means of a segment 35 and a suitable locking dog of ordinary construction operated by pinch lever 36.

A box 37, to receive the sweepings, is arranged within the frame 12 and comprises side walls 38, a front wall 39, a hopper shaped bottom 40 and a pan 41 arranged in rear and below the hopper shaped bottom and connected to the fixed downwardly and forwardly inclined rear plate 42 of the hopper shaped bottom by a curved wall 43. The box has its front portion arranged under the arched axle, between the vertical portions of said axle and the side walls of the box are attached to the axle by means of angle brackets 65 which are riveted or otherwise suitably secured to the vertical por-

tions of the arched axles and also to the side walls of the box. The hopper shaped bottom also includes a member 44, which is hinged at its front side as at 45 so that it 5 may be lowered so as to open at the bottom to discharge a load of sweepings from the box when desired. This closure member or dump member 44 is raised and lowered by means of a roller 45' and a chain 46, the 10 roller being mounted in bearings 47 near the front upper corners of the box. Ratchet wheels 48, 49 are on said roller. The ratchet wheel 49 is engaged by a pawl 50. A lever 51 for rotating the roller when desired, is 15 pivotally mounted as at 52 and has a pawl 53 for engagement with the ratchet wheel 48. The pawl 50 is provided with a suitable treadle which may be depressed to cause the pawl to disengage the ratchet wheel 48. The 20 pawl 53 may be manually disengaged from the ratchet wheel 48 to release the roller 45 and hence permit the load to be dumped from the box as will be understood. The box is provided on opposite sides, at a suitable 25 distance from its rear end, with supporting wheels 54 which are mounted on stub spindles that project from opposite sides of the box. To the bottom of the pan 41 at 56' is hinged a member 56 adapted to conform 30 with inequalities of the street surface. The hinged member of the pan bottom is provided with supporting rollers 57, and also has a flexible downwardly and rearwardly inclined flange 58, which in practice may 35 be made of rubber, leather or any other suitable material, and which bears directly on the street surface and in front of the revolving brush, so that the sweepings which are taken up by the brush are thrown forwardly 40 therefrom onto the bottom of the pan.

A revoluble loader 58 is arranged above the pan and comprises a shaft 59, radial arms 60 and curved blades or sweeps 61 at the outer ends of said radial arms. The 45 shaft 59 is mounted in bearings 62 in the side walls of the box and at one end of said shaft is a sprocket wheel 63 which is connected by an endless sprocket chain 64 with a sprocket wheel 21 so that said loader is 50 driven by power transmitted thereto from the revoluble brush, and is rotated in the same direction as the brush. The bar 13^a is provided with a loop 59^a to clear the shaft 59.

55 To raise and lower the rear end of the trailing frame as required I provide a lever 66 which is mounted as at 67 on the arched axle, as connected by a link rod 67' to the arched cross bar 14 of said frame; and said 60 lever is secured in adjusted position by means of a segment 68 and a suitable locking dog operated by pinch lever 36.

A seat 70 for the driver of the machine is

mounted on the arched axle. The levers 32, 5^a, and 66 are in easy reach of the driver, 65 so that he is enabled to readily control the operation of the machine.

Having thus described my invention I claim:—

1. In a street cleaning machine an ambulant frame, a trailing frame in rear of the ambulant frame, a revoluble brush mounted in the rear portion of the trailing frame, a box carried by the ambulant frame and arranged within the trailing frame, said box 75 having a pan at its rear side arranged in front of the revoluble brush, and a revoluble loader arranged above said pan and to throw the sweepings from the pan into the box, the box being provided with a hopper shaped bottom arranged immediately in front of the pan and having a hinged discharge member.

2. In a street cleaning machine, an ambulant frame including an axle and wheels 85 thereon, one of said wheels having a master gear, a box attached to and arranged under and extending rearwardly from the axle, said box having a pan at its rear side and being provided with supporting wheels to 90 bear on the ground, a trailing frame arranged on opposite sides of the box extending rearwardly therefrom and pivotally connected at the front end to the axle, a revoluble loader having bearings in the side walls 95 of the box, a revoluble brush arranged in rear of the pan and having bearings in the trailing frame, means to raise and lower the rear end of the trailing frame together with the brush, driving connections between the 100 brush and the loader, a stub shaft mounted on one side of the trailing frame and having a gear engaging the main gear and also having a sprocket wheel, a second sprocket wheel on the shaft of the revoluble brush, 105 and an endless sprocket chain connecting said sprocket wheels.

3. In a street cleaning machine, an ambulant frame and trailing frame in rear of the ambulant frame, a revoluble brush mounted 110 in the rear portion of the trailing frame, a box carried by the ambulant frame and arranged within the trailing frame, said box having a pan at its rear side arranged in front of the revoluble brush and provided 115 with a hinged rear member having supports which bear on the ground, and a revoluble loader arranged above the pan to throw the sweepings from the pan into the box.

In testimony whereof I affix my signature 120 in presence of two witnesses.

JOSEPH WYBORSKI
